UNITED STATES PATENT OFFICE.

ALEXANDRE LAMBLIN, OF PARIS, FRANCE.

COOLING RADIATOR FOR AEROPLANES AND OTHER VEHICLES AND PROCESS FOR ITS
MANUFACTURE.Original application filed January 7, 1925, Serial No. 1,012, and in France January 24, 1924. Divided and
this application filed January 9, 1928. Serial No. 80,186.

This invention relates to cooling radiators for aeroplanes and other vehicles, comprising easily manufactured cooling elements, having a small weight and a large radiating surface. These elements are characterized by their cross section being in the shape of a V, the branches of which have a large surface of contact with the cooling air. The present application is a division 10 of my co-pending patent application 1012, filed January 7th, 1925.

Several constructions according to the invention are shown by way of example in the accompanying drawings in which:

15 Figure 1 is an elevation of a cooling element according to the invention.

Figure 2 a cross section of the said element on line 2—2 of Figure 1.

20 Figure 3 a longitudinal section of the element on line 3—3 of Figure 2.

Figures 4 and 5 two cross sections of two modified constructions of the element shown in Figures 1—3.

25 Figures 6—9 cross sections of a third modified construction of the element of Figures 1 to 3, these four sections corresponding to four successive stages of manufacture of the said element.

Figure 10 is a longitudinal section of a 30 radiator with annular headers, provided with elements like those in Figures 1 to 9, this radiator being mounted on the fuselage of the aeroplane.

Figure 11 is a cross section of this radiator on line 11—11 of Figure 10.

35 Figure 12 is a section similar to that of Figure 10, of another construction of the radiator.

Figure 13 is a longitudinal section of a 40 radiator like the preceding ones, provided with a special air regulating device.

Figure 14 is a partial plan of the said radiator.

Figure 15 is a cross section of this radiator on line 15—15 of Figure 13, and

45 Figure 16 is a side elevation, on an enlarged scale, of a shutter of the air regulating device of the radiator shown in Figures 13—15.

50 The cooling element 50 (Figures 1 to 3) is constituted by two sheet metal plates 51 and 52 bent along their central rib so as to form two different angles α and β . These

two plates are inserted into each other (Figure 2) and, owing to the difference in the angles α and β , the two plates 51 and 52 form between them a free space. Their edges 53 are applied to each other and then soldered or otherwise joined together. An element is thus obtained, the cross section 60 of which has the shape of a V.

A hot water inlet 54 and a cooled water outlet 55 are provided in the bottom of the element thus constituted.

The water to be cooled circulates in the direction of the arrows 56 in the free space left between the plates 51 and 52. The air circulates both between the two wings of the V formed by the element and outside these two wings as shown by the arrows 57 70 in Figure 3.

An element of light weight and with great radiating surface is thus obtained, which element ensures a division of the air current into elementary veins properly guided 75 along the element.

The element just described can be manufactured by means of different processes.

Thus, Figure 4 shows a modified construction of the element of Figures 1 to 3, in which the plate 51 has two turned over edges 58 which cover the edges of the plate 52 and are soldered to them; a much stronger assembly of the plates 51 and 52 on each other is thus obtained.

85 The cooling element with V-shaped cross section could also be made, as shown in Figure 5, from a single plate 59 suitably bent over; one of the free edges 60 of this plate is bent over and soldered to the other edge. 90 This method of manufacture offers the advantage of reducing by half the number of soldered joints and therefore of simplifying the manufacture and reducing to a great extent the risk of leakage of water.

95 The new elements with V shaped cross section could also be manufactured in a single piece without any soldering as indicated in Figures 6 to 9. A round or flattened tube 61 (Figure 6) is used. This tube 100 is stamped out or expanded so as to leave flat one of its faces 61¹ and bending the other face 61² (Figure 7). Finally, the element is given its final shape by bending or stamping out (Figures 8 and 9).

105 The invention covers the previously de-

scribed cooling elements (Figures 1 to 9) in themselves, whatever be the special grouping in which these elements are used; the invention covers also certain arrangements or 5 methods of grouping hereinafter described and offering special advantages.

Thus, Figures 10 and 11 show a radiator constituted by a certain number of elements with V-shaped cross section connected by 10 means of tubes 65, 66 to a front header 62 and a rear header 63 placed in the interior of the hood 64 of the vehicle and fitting the rounded shape of the said hood (Figure 11).

Water inlet and outlet ducts 67, 68 connect the headers 62, 63 to the jacket of the 15 engine.

The arrows 56 and 57 show respectively the circulation of the water and that of the air in the radiator.

20 It will be seen in Figure 11 that owing to the arcuate shape of the headers 62, 63, the elements 50 with V-shaped cross section diverge relatively to each other starting from the headers. It is therefore possible 25 to bring the bases of the tubes 66 as close together as may be desired on the headers, without the V-shaped elements 50 fouling each other; on the contrary, these elements, in diverging from each other, always leave 30 between them a free passage for the cooling air.

Thus, the combination of V-shaped elements with curved, for instance circular or 35 semi-circular, headers makes it possible to fit the greatest possible number of elements on a given length of the header, and to obtain for a radiator of a given weight, as great a radiating surface as possible.

To facilitate the penetration into the air 40 of the radiator with V-shaped elements, and to enable it to fit more easily the rounded shape of its support, for instance of the aeroplane fuselage, these elements can be given a longitudinal shape convex or concave towards the exterior of the radiator, 45 as indicated in Figure 12.

The invention covers also the combination 50 of a radiator with elements with straight section in the form of a V, such as the radiators of Figures 1 to 12, with means enabling two air circulation currents to be admitted into the said radiator, one longitudinally of the cooling elements, and the other transversely of the said elements; means such as shutters, 55 or screens make it possible to regulate advantageously at will one or the other of the two currents or both together.

Figures 13 to 16 show a construction of 60 that arrangement.

Under the hood 73 of the aeroplane is 65 mounted a radiator with headers 62 and 63 on which are branched elements 50, the radiator being such as that of Figures 10 and 11 for instance. This radiator replaces thus 70 a portion of the hood and is adapted to the

general shape of this hood and the elements 50 project freely into the atmospheric air.

An air inlet chamber 110 is provided in the hood. A shutter 84 is pivoted at 85 in front of the radiator. Other shutters 74 are provided in the interior of the radiator; each of these shutters is pivoted about a pin 75 (Figure 16) and secured to a control rod 76 and to a return rod 77 with a spring 78.

All the control rods 76 of the shutters 74 are connected together by a coupling rod 79 which the pilot can pull in the direction of the arrow 80 by means of well known control mechanism, with lever and toothed quadrant for instance, not shown in the drawings.

The radiator of Figures 13-16 works as follows: when the pilot does not pull on the coupling rod 79; the springs 78 pull the rods 77 in the direction of the arrow 81 (Figure 16) and keeps the shutters 74 applied closely against each other; these shutters thus completely close the interior of the radiator. Under these conditions, the radiating group 50 is traversed only in the ordinary manner by the air current 106; the veins of this current are besides guided by the whole of the shutters 74 which form an air guide plate.

When the pilot wishes to get a greater cooling of his engine, and to increase the supply of air to his radiator, he operates the control mechanism so as to pull in the direction of 80 the coupling rod 79, all the shutters 74 turn about their spindles 75 and cock the springs 78. Under these conditions the air current 83 which gets into the interior of the bonnet 73 through inlets not shown in the drawings, is divided into elementary currents 83¹, 83² . . . etc. which pass between the shutters 74 and combine with the air current 106 which normally plays on the elements 50.

In short, the combination described in the foregoing makes it possible to obtain three entirely different states of working of the 110 radiator.

1. The shutter 84 is lowered, and the shutters 74 are applied against each other; the air current 106 is stopped by 84, and the air current 83 by 74, and the radiator works with the minimum cooling.

2. The shutter 84 is raised and applied against the hood (dotted position in Figure 13); the shutters 74 are applied against each other; the air current 106 passes freely through the radiating group 50, but the air current 83 is stopped by the shutters 74, and the radiator works thus with the mean or average cooling.

3. The shutter 84 is raised and applied against the hood, and the shutters 74 are opened in the positions shown in Figure 13; the air currents 83 and 106 pass through the radiator as already explained, and the radiator works with the maximum of cooling.

It is obvious that it would be possible to obtain a whole range of different air supplies between the three states of cooling hereinbefore indicated, by raising more or less the 5 shutter 84 and opening more or less the shutters 74.

It will be seen that in the construction of Figures 13 to 16, when the shutter 84 of this radiator is raised and applied against 10 the hood 73 of the aeroplane, and when the shutters 74 are opened as shown in Figure 13, the air veins 83 and 106 are mixed together and superposed in the free spaces 90 provided between the adjacent elements 50 15 (Figure 15). As these free spaces 90 decrease in their outside portions owing to the inclination of the wings of the V, the air currents 83, 106 are held and guided between the adjacent wings of the adjoining V elements. 20

The air currents 106 alone remain in the inner free space 91 of the V constituted by each element 50 and continue to circulate freely in the said V without any possibility 25 of being deflected by the auxiliary air current 83.

I claim:

In a cooling radiator for aeroplanes and other vehicles, the following combination; a front header, a rear header, tubular elements 20 of V-shaped transverse section, said elements having free spaces therebetween and being interposed between the front and the rear headers and disposed longitudinally with respect to the direction of movement 25 of the vehicle, shutters pivotally disposed on the base portions of the tubular elements, means for controlling said shutters in a manner either to open said shutters with respect to each other in order to permit a 30 transverse current of air to penetrate between the elements or to close said shutters with respect to each other, and means for guiding a current of air longitudinally to circulate in part between the wings of the 35 V of each element and in part between the free spaces formed between said elements, said shutters serving also to guide said latter current of air, when said shutters are closed with respect to each other. 40 50

In testimony whereof I affix my signature.
ALEXANDRE LAMBLIN.
